UNITED STATES PATENT OFFICE.

WELLINGTON W. MUIR, OF BALTIMORE, MARYLAND.

CARBURETER.

1,143,986.

Specification of Letters Patent. Patented June 22, 1915.

Application filed March 18, 1914. Serial No. 825,476.

To all whom it may concern:

Be it known that I, WELLINGTON W. MUIR, a citizen of the United States of America, residing at Baltimore, State of Maryland, have invented certain new and useful Improvements in Carbureters, of which the following is a specification.

This invention relates to carbureters and particularly to a carbureter of the float feed straight tube type having no moving parts aside from the float regulated supply valve and the throttle. Carbureters of this general type are not broadly new, as mixing devices composed entirely of static members have been known to the art from the earliest stages of its development; but in the use of these carbureters various difficulties have been encountered. Of these difficulties the principal one is that the richness of the mixture increases with the speed so that with a fuel nozzle and a head of fuel sufficient to supply the engine at low and medium speeds, economical and efficient running at high speeds cannot be had, because with the increased vacuum, the supply of fuel increases out of proportion to the requirements of the engine. As the mixture becomes too rich, there is a loss not only of economy and efficiency as to the fuel consumption, but the efficiency of the engine in point of power developed is also reduced. In the carbureter of the present invention this difficulty is overcome, in the first instance by so arranging the fuel feed that at high speeds instead of pure gasoline or other liquid hydrocarbon being supplied to the aspirating nozzle an emulsion of gasoline and air is fed, and, second, as the speed increases, and hence the vacuum at the nozzle and the rate of feed, the air pressure in the float chamber and hence the effective head of the liquid fuel is decreased, so that the fuel consumption instead of being proportionate to the vacuum, thus increasing the richness of the mixture with the speed of the engine as occurred with the former carbureters of this type, is regulated, the mixture being held to the best proportions, and the quantity of fuel fed, though it increases in actual amount at high speeds, decreases in its ratio to the vacuum and the speed of the engine.

Another difficulty which has been encountered in practically all carbureters, is that incident to breaking up the gasoline, *i. e.*, spraying or atomizing. It is of course

important that the mixture of gasoline and air should be as uniform and intimate as possible. For this purpose various expedients have been tried, but it is difficult to prevent the gasoline from entering the vaporizing chamber in the form of a column of liquid which is partly atomized and partly formed into globules which enter the cylinder. These comparatively large bodies of liquid are not consumed because the interior is protected by the portions near the outer surface from the action of the oxygen in the air and combustion is thus prevented or rendered imperfect. In this way a large amount of gasoline is wasted by being passed out through the exhaust and the cylinders and valves become carbonized. To overcome this difficulty in the instance of the present invention, a particular type of nozzle has been provided. This consists of a comparatively large tube with a small exit opening or nozzle. Within this large tube and placed centrally thereof so as to leave an annular passage, is a central tube open at its lower end to the air and at its upper end registering with the nozzle opening. The outer tube is contracted at this point, there being an internal annular shoulder around the nozzle. Gasoline is supplied to the annular passage. The central tube being open at its lower end, forms an inlet for air entering in response to the vacuum of the engine. The gasoline or other liquid fuel thus introduced is drawn up the annular passage and turned inward radially at the nozzle, bringing it in the form of a thin film directly in the path of the entering air which atomizes it most completely, the spreading of the gasoline in the form of a film and presenting it in this form being particularly effective in preventing the formation of globules.

Another feature of the invention is a priming device connected to the manifold at a point between the throttle and the engine. The primer consists of a cup open at the top connected to the fluid chamber by a passage leading to a nozzle at the bottom of the cup. The cup is connected to the manifold between the throttle and the engine by means of a tube, the end of which preferably incloses the point of the nozzle at the bottom of the cup, leaving an annular opening around the nozzle. When the engine is turned over, the gasoline from the cup is

sucked up and fed to the manifold, and as the engine continues to run, the gasoline fed through the primary nozzle is mixed with air drawn through the annular opening in the end of the tube around the nozzle and the mixture thus formed is sufficient to run the engine at a low rate of speed, but for ordinary purposes the throttle is immediately moved toward open position so that the engine runs at a higher speed. However, the carburetor is double in its operation, the primer always serving to feed a small quantity of mixture to the manifold, so that if for any reason the flow through the main carburetor should be checked as by a particle of dirt or the like, the engine will continue to turn over, consuming the fuel supplied by the primer, but the primer may be varied, changed or removed without departing from the invention. It will also be noted that the primer or secondary carburetor is subject to the same regulation at high speeds by reduction of the head due to air pressure, as is the main carburetor, so that the tendency to increase the richness of the mixture at high speeds is overcome.

In the accompanying drawings I have illustrated my invention in its preferred form.

Figure 1 is a plan. Fig. 2 is a vertical central section on the line 2-2 of Fig. 1. Fig. 3 is a vertical section on the line 3-3. Fig. 4 is a horizontal section on the line 4-4 of Fig. 2. Fig. 5 is a plan of a modified form. Fig. 6 is a vertical section of the same on the line 6-6. Fig. 5.

Referring to the drawings by numerals, each of which is used to indicate the same or similar parts in the different figures, the carburetor which is of the float feed type, consists of a float chamber 1 with the usual float 2 and float valve 3 controlling a fuel inlet supply pipe 4. In the form of the device shown, the float chamber is integral with the straight tube 5 having an air inlet 6 and being secured to the manifold by means of a flange 7. The straight tube is provided just above the air passage with a tapered sleeve 8 referred to herein as a Venturi tube or carbureting passage in which is the nozzle 9. The latter is formed in the upper end of the straight tube 10, the walls of the tube being near the end turned inward, forming an inwardly projecting shoulder 10' which gives a nozzle opening 10" of reduced area. The tube 10 as shown is carried by a centrally apertured screw-plug 11 seated in the bottom of the straight tube, and within the tube 10 is a second tube 13 carried by an apertured screw-plug 11, the tube 13 being sufficiently small to leave an annular passage 15 between the inner and outer tubes. This passage is connected by a passage 16 with the float chamber. The inlet end of the passage 16 where it receives the fuel

from the float chamber 1 is, in the form of the invention illustrated, expanded into a conical entrance 17 which is formed in the bottom wall of a recess 18 in the float chamber. In this recess is a valve 19 vertically placed and having its lower end in the form of a cone corresponding to the conical entrance 17 and placed therein, giving an annular conical opening 17'. The upper end of this valve is threaded at 20 to fit a threaded opening 21 in the body of the float chamber, so the plug 19 is adjustable up and down to determine the size of the opening 17'. The lower end of the valve plug 19 up to the threaded portion which is closed, is made hollow, forming a cylindrical passage 23 having a reduced opening 24 at its lower end located in the beginning of the fuel supply passage 16. The valve 19 is perforated at 25 near the upper end of the opening 23 and above the float, and the float chamber 1 itself is perforated at 26, the openings 24 and 25 being of a definite relative proportion as hereinafter described.

Referring to Figs. 1, 3 and 4, the carburetor is provided at one side with a priming cup 27 open at the top and connected at the bottom to the float chamber by means of a passage 28 terminating in a nozzle 29, the capacity of which is regulated by means of a needle valve 30 threaded at 31 to engage a threaded opening in the carburetor body. The priming cup 27 is connected to the intake between the throttle and the engine by means of a pipe or tube 32 at a point 34 100 beyond the throttle 33, the tube being passed down into the cup 27 and having its inlet opening 35 enlarged to inclose the nozzle.

The operation will be easily understood from the preamble and description taken in connection with the drawing. When the engine is stationary, the priming cup fills up to the level of the fuel in the float chamber. In starting the throttle is closed or nearly closed and the vacuum of the engine 110 as it is turned over, draws the fuel out of the priming cup 27 and injects it into the straight tube or manifold beyond the throttle. The priming charge is thus supplied to the engine, but after starting, the primer 115 continues to operate as a small carburetor, the nozzle 29 acting as an aspirating nozzle. The gasoline thus fed is mixed with the air which passes through the annular opening 15 between the nozzle 29 and the flaring end 35 120 of the pipe 32, giving mixture sufficient to run the engine at a low speed.

In this connection it is interesting to note that the carburetor, to accomplish the regulation described, operates at different times 125 under four different sets of conditions or in four different ways, the operation just described represents the first set of conditions or first method of operation. In this case the throttle is closed, the entire fuel supply 130

being taken from the primer or priming carburetor. Thus regulated, the engine runs at its lowest rate of speed.

The priming carburetor always acts in conjunction with the main carburetor during the running of the engine, though it is within the scope of my invention to provide means for closing the connection if so desired, and this carburetor is subject to the regulation by reduction of the air pressure in the float chamber as hereinafter described.

When the engine gets under way, the throttle being open, the vacuum causes the aspiration of the fuel at the nozzle 9. This mixes, first, with the air entering the passage 13 and then with the air in the Venturi tube which enters through the air inlet 6 forming an exceedingly intimate and uniform mixture which is fed forward to the engine in the usual way. Here the second set of running conditions is in force. At this time the carburetor has the regular operation of a constant level aspirating carburetor. The gasoline fed to the nozzle 9 is determined by the adjustment of the valve 19, that is, by the size of the opening 17', as all the gasoline fed to the nozzle 9 must flow through this opening at the particular pressure existing, *i. e.*, the difference between the pressure at the bottom of the float chamber and that in the Venturi tube or more particularly in the feed pipe leading to the nozzle 9.

As the speed increases, pressure in the Venturi tube, as compared to that in the float chamber, decreases, the third set of running conditions comes into effect and the carburetor operates after the third method referred to. With the increase of vacuum the tube 23 is emptied of fuel because of the increased suction and the nozzle 9 begins to draw air from the top of the float chamber through the perforations 25 via the passage 23 and the outlet 24 of the valve 19, so that the carbureting operation is shifted from the opening 10" to the opening 17', the first mixing taking place at this point. The mixture thus formed is diluted with air at the nozzle 9 and later in the venturi. In this way the quantity of fuel fed as compared to the height of the vacuum in the venturi is reduced but the air enters the float chamber through the opening 26 in sufficient quantities to maintain the pressure on top of the gasoline, so that the only reduction is accomplished by feeding a mixture of air and gasoline to the nozzle instead of pure gasoline.

As the speed increases approaching the highest rate, the fourth set of running conditions becomes effective and the rate of fuel feed as compared to the height of the vacuum, is again decreased by the reduction of the air pressure in the float chamber. This is made possible by the fact that the

openings 24 and 26 are so related that at a predetermined speed which is near the highest for which the carburetor is adapted, the supply of air drawn from the float chamber is greater than that entering through the openings 26, and thus a vacuum is created in the float chamber and the head or pressure on the gasoline supply at this point is reduced, thus reducing the tendency of the fuel to flow to the nozzle 9. In this way the ratio of the fuel consumed to the height of the vacuum in the Venturi tube is further decreased and the existing tendency to increase the richness of the mixture is overcome.

It is thus made apparent that regulation is accomplished by the four different methods of operation of the carburetor,—the first being the lowest speed with gasoline fed through the priming carburetor only; the second being the normal low speed running of the engine with gasoline flowing in full volume unmixed through the opening 17' to the nozzle 9. For running under these conditions the carburetor is adjusted as to the size of this opening or otherwise the size of the opening 17' is determined by the quantity of gasoline required to give the most efficient running at this speed. The third method of running is with the gasoline drawn from the passage feeding the nozzle 9 up to the point where the opening 24 is uncovered. At this time mixing first takes place at 17' and subsequent dilution at the nozzle 9 and in the venturi, the determining elements and the elements to be determined at this speed being the size of the opening 24. The fourth set of running conditions is with the air being drawn through the opening 24 faster than it enters the float chamber through the openings 26, giving a vacuum over the gasoline in the float chamber and a reduced head. The determining element under these circumstances is the relation of the size of opening 26 to the size of opening 24, and this opening 26 must be of such size and so related to the opening 24 that the amount of air exhausted is sufficient to create the desired vacuum over the fuel in the float chamber, and thus reduce the head so as to overcome the tendency to increase the fuel flow as related to the engine vacuum with consequent increase of the richness of the mixture.

In Figs. 5 and 6 I have illustrated my carburetor in connection with a horizontal instead of a vertical straight tube. In this instance there is a horizontal tube 40 having an air inlet 41 with a flange 42 by which it is connected to the manifold. In this carburetor the venturi 43, instead of being vertical, lies in a horizontal position, the straight tube and venturi being apertured at 44 to admit the fuel pipe 45 with an enclosed air pipe 46 corresponding to the

concentric tubes in the previous modification, these tubes being mounted on centrally apertured screw-plugs 47 and 48 seated in a bracket 49 formed integral with or otherwise connected to the body of the instrument, the arm of the bracket being apertured to form a passage 50 leading to the annular passage 51 between the walls of the tubes 45 and 46. Otherwise the two carburetors are of precisely similar construction and the parts are so nearly identical that they need not be described.

The invention has been set forth specifically and in detail in order that its operation may be clearly understood. However, the specific terms herein are used descriptively rather than in their limiting sense and the scope of the invention is defined in the claims.

20 I claim:

1. In a carburetor for internal combustion engines to be connected to the intake and operated by the vacuum of the engine, a carbureting passage, a fuel nozzle therein, a constant level fuel supply chamber, a fuel passage connecting the nozzle to the supply chamber, means in the form of a chamber open to the air space of the fuel supply chamber above the normal gasoline level and below into the fuel passage, for supplying air to the fuel passage at high speeds taking it from the fuel supply chamber, the fuel supply chamber having openings for the admission of air sufficient to maintain atmospheric pressure over the liquid at low speeds but insufficient to supply the air taken from the fuel supply chamber at high speeds so the air over the fuel in the fuel supply chamber is partially exhausted reducing the pressure on the fuel when the vacuum in the carbureting passage is increased beyond a certain point.

2. In a carburetor, a constant level fuel supply chamber, a carbureting passage, a fuel nozzle in the carbureting passage, a fuel passage leading from the fuel supply chamber to the nozzle and an air tube delivering air into the fuel passage, the tube being in the form of a hollow plug valve regulating the fuel supply to the nozzle.

3. In a carburetor, a fuel supply chamber, a carbureting passage, a fuel nozzle in the carbureting passage, a fuel passage leading from the fuel supply chamber to the nozzle and an air tube taking air from the fuel chamber over the level of the fuel therein and delivering air into the fuel passage, the air tube being in the form of a hollow plug valve adapted to determine the capacity of the fuel passage leading from the fuel supply to the nozzle.

4. In a carburetor, a fuel supply chamber, a carbureting passage, a fuel nozzle in the carbureting passage, a fuel passage leading from the fuel supply chamber to the nozzle

and an air tube taking air from the fuel chamber over the level of the fuel therein and delivering air into the fuel passage, the air tube being in the form of a hollow plug valve adapted to determine the capacity of the fuel passage leading from the fuel supply to the nozzle, and means for adjusting the said valve to vary the capacity of this passage.

5. In a carburetor, a fuel supply chamber, a carbureting passage, a fuel nozzle in the carbureting passage, a fuel passage leading from the fuel supply chamber to the nozzle, a valve controlling the size of the opening in the passage, means for adjusting the valve to vary the size of the opening, the valve being hollow and having an opening at the bottom and also an opening near the top above the level of the fuel, the supply chamber also having an air inlet opening above the level of the fuel, and means tending to keep the height of fuel in the chamber at a substantially constant level.

6. In a carburetor, a fuel supply chamber, means tending to maintain a substantially constant level of fuel in the chamber, a carbureting passage, a fuel nozzle in the carbureting passage, a fuel passage leading from the fuel supply chamber to the nozzle, an air tube taking air from the space in the fuel chamber above the fuel level and delivering it to the fuel passage, the fuel chamber having an inlet air opening also above the level of the fuel, the outlet opening of the air tube and the air inlet opening of the fuel chamber being so proportioned that at high speeds the air passing through the tube exceeds in quantity that entering the fuel chamber through the opening.

7. In a carburetor, a fuel supply chamber, means tending to maintain the level of the fuel therein substantially constant, a carbureting passage, a fuel nozzle in the carbureting passage, a fuel passage leading from the fuel supply chamber to the nozzle, an air tube taking air from the fuel supply chamber above the level of the fuel therein and delivering it to the fuel passage, the carburetor being so arranged that it operates in three different ways, at low speed the fuel flowing in a full uninterrupted stream through the fuel supply to the nozzle, the air tube being filled with gasoline to the level of the liquid in the float chamber at a high speed, the gasoline being withdrawn from the air tube, air entering the fuel supply passage through this tube, so that the fuel is diluted, the pressure on the gasoline in the chamber being substantially equal to that of the outside atmosphere, and at the highest speed the air passing through the air tube from the fuel chamber exceeding the air entering the fuel chamber through the air inlet, giving a vacuum over the fuel and a constant reduction of fuel head.

8. In a carbureter, a fuel supply chamber, means tending to maintain the fuel level therein constant, a carbureting passage, a fuel nozzle in the carbureting passage, a fuel passage leading from the fuel supply chamber to the nozzle and an air tube delivering air into the fuel passage, the tube being in the form of a hollow plug valve regulating the fuel supply to the nozzle, the plug valve being perforated above the level of the liquid and the fuel chamber having a small opening only sufficient to supply a volume of air equal to the volume of fuel used at intermediate speeds.
9. In a carbureter, a fuel supply chamber, means tending to maintain the fuel level therein constant, the chamber being closed to the entrance of air except as to an inlet of predetermined size, a carbureting passage, a fuel nozzle therein, a fuel passage leading from the fuel chamber beneath the level of the liquid to the nozzle, a plug valve for regulating said passage, the plug valve having therein an air passage leading from the air space in the fuel chamber to and into the fuel passage.
10. In a carbureter having a constant level fuel supply chamber, an aspirating nozzle, a primer consisting of a cup open at the top and having at the bottom a nozzle connected to the fuel chamber below the fuel level, a tube leading from within the cup to the engine vacuum, the lower end of the tube inclosing the nozzle, and means for exhausting the air over the fuel in the fuel supply chamber by way of the aspirating nozzle.
11. In a constant level carbureter having a float chamber, an aspirating nozzle, a fuel supply passage leading to the nozzle and an air tube normally filled with gasoline having intake openings in the float chamber above the normal level of the liquid, the air tube emptying into the fuel supply passage so that the mixing operation takes place first at the nozzle and later, as the speed and vacuum increase, is shifted to the end of the air tube, which is emptied of gasoline at this time and serves as an air passage delivering air to the fuel passage, the float chamber having inlet openings which are sufficient to supply the air removed by the air tube at low speeds, but are insufficient to supply the air taken at the highest speeds so that at high speed, a vacuum is created in the float chamber reducing the fuel head.
12. In a carbureter, a fuel spray nozzle, a fuel supply passage therefor, a carbureting passage, a main fuel nozzle located in said passage, the passage being connected to the engine vacuum, a constant level fuel supply chamber and means for delivering air from the said chamber through the nozzle, taking it from a point above the normal level of the liquid in that chamber, the chamber having restricted openings for the admission of air whereby a mixture of air and gasoline is fed to the nozzle, the restricted openings being sufficient to maintain atmospheric pressure in the said fuel chamber at low speeds but insufficient to supply the air taken from the fuel chamber at high speeds so that the pressure drop at the spray nozzle at increased speeds is communicated in a modified degree through the fuel supply passage to the space above the fuel in the fuel supply chamber to regulate the fuel supply to the nozzle.
